CENSER

Leo R. Le Tang, Cincinnati, Ohio

Application August 30, 1948, Serial No. 46,771

8 Claims. (Cl. 21—116)

1

The present invention relates to a censer or thurible adapted for use in ecclesiastic ceremonies and has for an object the provision of a device of this kind that is free of various difficulties that are sometimes experienced in the preparation and use of such devices.

Another object of the invention is to provide a censer that is constructed so as to provide for a maximum of heat dissipation directly to the atmosphere and for a minimum of heat conduction to the exterior parts thereof, thus affording a high degree of safety to those handling the same.

Still another object of the invention is to provide a ventilated censer that lends itself to unique and elegant ornamental design and to a variety of metals or metal finishes.

A still further object of the invention is to provide a censer adapted to be suspended by a single chain, without the dangers of known one chain censers.

Yet another object of the invention is to provide an easily and inexpensively arranged assembly of concentrically disposed and spaced related parts affording a greatly reduced metallic heat conductivity from the incense cup to the exterior ornamental and supporting parts of the device and affording selective disposition of the cover member above or below the cup.

These and other important objects are attained by the means described herein and exemplified in the accompanying drawings in which:

Fig. 1 is an elevational view of a censer embodying the invention.

Fig. 2 is a view taken on line 2—2 of Fig. 1 showing the pan partly broken away and the support ring partly in section.

Fig. 3 is a vertical sectional view of the device showing in full lines the position of the cover in an operative position over the pan, and in dotted lines the position of the cover in its inoperative position.

Fig. 4 is a view taken on line 4—4 of Fig. 2.

Censers or thuribles have heretofore consisted generally in a hollow ornamental body, a cover adapted to be lifted and lowered over the body and a cup or container for fire and incense materials, the body having three suspending chains, while a fourth chain is attached to the top of the cover for lifting it. The three body suspension chains are sometimes passed through three of the ventilating holes near the bottom of the cover to guide the latter gravitationally into closing position on the body. These structures become quite hot during the period of prepara-

tion and ceremonial use and the suspending chains sometimes cause inconvenience to the users, particularly when the cover is lifted to add incense to the glowing material in the incense cup or container.

By the means of the present invention the previously experienced difficulties are completely eliminated and a device is provided that is simpler to fill and use, said device being, by the nature of its construction, suited to a new and enlarged range of ornamental design.

In the device as exemplified in the drawings a plurality of bracket members 7, 8 and 9 are provided with pairs of lugs 10—10, 11—11, and 12—12 respectively. These lugs are preferably spaced apart equal distances on each bracket, but the lugs on each succeeding bracket are vertically offset from the top and bottom of said bracket by a distance equal to the thickness of the lugs. This permits the upper and lower sets of lugs 10, 11 and 12 to be superposed in stacked relation and to be connected as a unit at the top by a threaded rod 13 and at the bottom by a screw 14. The bottom lug 10 of the upper group and the top lug 12 of the lower group are drilled and tapped to receive the thread of said screw members 13 and 14 respectively while the remaining lugs of both groups are merely drilled for the passage of said screws. A dish type base or foot 15 is attached to the lower lug 10 by the screw 14 and the lower ends of the brackets 7, 8 and 9 may rest on the top face of said base. The center of gravity is thus disposed in the vertical axis passing through screws 13 and 14 particularly when the brackets are spaced apart uniformly at 120° about such axis.

A drilled ornamental knob 16 of plastic material or other low heat conductive material is passed over the threaded rod 13 and a threaded ball nut 17 is screwed onto the threaded end of the rod and is further provided with a pivoted ring 18 to which a suitable length of chain 19 is attached.

Rigidly supported between the brackets is an ornamental hollow body 20 of generally hemispherical or cup form having an enlarged bottom opening 21 and further having about its upper horizontal edge a circumferentially arranged ring of openings, some of which openings are accurately spaced holes, while the remainder of said openings are round bottomed vertical slots which extend through the top edge 22 of the body 20 in uniformly spaced relation to each other and to said holes in the manner which will now be described. One hole 23 and an opposed slot 24

are disposed on a given diameter of body 20, and another hole 25 is disposed at 90° thereto, said hole 25 being diametrically opposed to a specific slot 26. A slot 27 is spaced 120° from slot 24 and is disposed between slot 26 and hole 23, while the last slot 28 is disposed between holes 23 and 25 and is spaced 120° from slots 24 and 27.

The brackets 8 and 9 each have relatively long dowels 29 projecting inwardly and horizontally toward the vertical center axis of the device and these dowels extend through and beyond the slots 27 and 28 in body 20 for the dual function of supporting the body at two points near the top and of accurately spacing the brackets 8 and 9 at an angle of 120° about said vertical axis. The bracket 7 has a similarly located and shorter dowel 30 which passes through slot 24 and terminates substantially flush with the inside face of body 20. The dowels 29 and 30 may be cast integrally with the several brackets or rigidly inserted therein in any desired manner. The several brackets have spacer and support bosses 31 located so as to contact the exterior of body 20 at three points 120° apart near the bottom and to thereby space the body from the brackets and to cooperate with dowels 29 and 30 in rigidly supporting the body on the brackets with a minimum of metallic contact through which heat may travel by conduction.

An incense cup 32 is provided with a peripheral lip or bead 33 from which the cup is suspended within an annular support 34. The ring or annular support 34 has in the exterior side wall thereof a pair of recesses or drilled holes 35 spaced 120° apart and adapted to receive the correspondingly reduced and shouldered ends 36 of dowels 29.

Midway between holes 35 is a tapped hole 37 which receives the threaded end of a screw 38 that passes through hole 23 in body 20 and serves to draw the ring rigidly against the ends of dowels 29 and a spacer bushing or tube 39 on said screw between adjacent sides of the ring and body.

A hollow hemispherical cover 40 has integral trunnions 41 and 42 extending outwardly at diametrically opposite sides and said cover is pivotally mounted on the body 20 by entering the short trunnion 41 into hole 25 in the body and then dropping the longer trunnion 42 into slot 26.

At this point it will be noted particularly in Figs. 2 and 3, that the brackets, the body 20, the cover 40 and the annular support member 34 are concentrically arranged in mutually spaced relation. It will also be noted that cover 40 may be moved on its trunnions, in the direction of the arrow, from an operative position as shown in Fig. 3 in full lines, through the unobstructed semicircular opening 43 between the body 20 and ring 34, at one side of the trunnions, to assume a wholly concealed relation inside the body and beneath the ring and cup.

The trunnion 42 is elongated and is retained in slot 26 by a small plate 44 that seats on the top edge of the body 20 and spans said slot 26 after the trunnion is entered in said slot. This is suitably attached to the body 20 by angular fingers 45 on the plate with screws 46 passing therethrough into said body. A rigidly attached or integrally formed rectangular block 47 on the trunnion 42 and a stem portion 48 with a threaded terminal end are adapted to cooperate with a reciprocably mounted finger piece and latch member 49 for manually moving the cover on its

trunnioned mounting and for slidably engaging the top edge of body 20 for holding said cover in the raised or operative position as shown in Figs. 1, 3 and 4. The member 49 has an enlarged axial bore 50 at its outer end and a reduced bore 51 aligned therewith at the inner end through which the reduced end of the trunnion passes. A coil spring 52 surrounds the trunnion and is held in compressed and concealed relation within bore 50 by a threaded abutment piece 53 which may enter the bore as the finger piece is pulled outwardly against the resistance of the spring. A projecting flange 54 on the finger piece (see Fig. 4) normally rests on the flat plate 44, that is in effect part of the top edge of body 20, and the top of block 47 and holds the cover against turning. When it is desired to uncover the incense cup the finger piece is pulled outwardly until the flange 54 is clear of plate 44 whereupon the finger piece and cover may be rotated to move the cover through the space 43 into the hollow interior of the body beneath the ring and cup. On reverse rotation the spring automatically shifts the finger piece toward the body and allows flange 44 thereof to assume a latching position.

As indicated in Figs. 2 and 4 the edge of cover 40 has slots 55 matching the slots 56 in the top of body 20 so that when the cover is raised the matching slots in the two members present the appearance of circular ventilating holes as shown in Fig. 1. The cover is furthermore provided with openings 560 arranged in decorative or symbolic ornamental form.

The operation and use of the censer will be readily understood. The heat from burning material in the cup 32 may rise and escape partly through openings 560 allowing the scented smoke to escape to the atmosphere. When the censer is swung by the chain the scent also escapes through the matching slots 56 and 55 in the body and cover respectively.

During continued use the cup 32 becomes hot and the rising heat draws cooling air up through opening 21 and allows it to flow between the inside of the body and the cup. Part of the heated air escapes to the atmosphere between the body and the cover and part passes between the support ring and the inside of the cover and escapes through openings 560.

Thus all the parts of the censer are subjected to ventilating currents of air and the relatively few and small metallic paths of conductivity require a long period of continued use before the exposed parts become noticeably heated. At no time during a normal period of use will those parts such as the brackets or the base 15 become hot enough to cause injury to the person or to articles that may come in contact with the device.

The devices of the invention are excellently balanced and may be tended and manipulated without danger or annoyance. Previously known single chain censers have presented dangers due to the fact that in opening the cover the chain would sometimes sag into the incense cup and become hot and also pull out liver coals from the cup and spill them, thus creating a fire hazard and a source of inquiry to the users. Due to the unique arrangement of the suspension of the present device in conjunction with the mode of operation of the cover all dangers are obviated. If desired three chains may be used on the present device if traditional three chain suspension be desired but the danger of entanglement of the chains as experienced with known triple chain suspensions is completely avoided.

What is claimed is:

1. In a censer the combination of a hollow body with an open top and an opening in the bottom thereof, a ventilated dome-shaped cover having a pair of diametrically opposed external trunnions thereon adjacent its bottom journalled in said body adjacent the top edge of the latter whereby the cover is supported for rotational movement in one direction to an inverted position wholly within the body for uncovering the open top of said body and for reverse rotational movement to an upright position substantially wholly outside the body for covering the open top of said body, one of said cover trunnions being extended beyond the body and having an integral block adjacent said body presenting a flat face substantially in a plane with the top edge of the body when the cover is in an upright position outside the body, and a latch member axially shiftable on said trunnion and spring biased toward said body, said latch member including a flange slidably guiding on said flat face on the trunnion and precluding relative rotation of the latch member and trunnion, said flange arranged and adapted to slidably engage on the top edge of the body under the influence of said spring bias when the cover is in upright position on the body for releasably retaining the cover in said position, said latch member being manually retractable against the resistance of the spring bias for retracting said flange from the top edge of the body and permitting unitary manual rotation of the latch member and trunnion whereby the cover is moved to and from said inverted position wholly inside the body.

2. In a censer the combination of a body, a series of brackets grouped about the body and having the upper ends connected together above the said body and the lower ends connected together below said body, bosses on said brackets supporting the bottom of the body in spaced relation to the brackets, dowels on said brackets extending through the body for effecting predetermined radial spacing of the brackets about the body and for retaining the body in seated relation on the said bosses, a trunnioned cover journalled at diametrically opposite sides of the body adjacent its top edge, a spring urged latch reciprocably and nonrotatably mounted on one of the cover trunnions and engageable on the top edge of the body for releasably holding the cover in upright position for substantially covering the open top of the body, an annular support of lesser size than the cover disposed concentrically within the upper interior of the body, a flanged incense cup removably seated in said annular support, the dowels in the brackets on one side of the axis of the trunnioned cover mounting being extended radially inwardly through the body and entered into the adjacent portions of said annular support, a spacer and screw member extending between the annular support and body midway the extended dowels for positively drawing the annular support against the extended dowels, a foot member connected to said brackets at the bottom thereof, and a suspension chain operatively connected with said brackets at the top.

3. In a ventilated censer the combination of a hemiglobular hollow body having an opening in the bottom, brackets grouped about said body in radially spaced relation, bosses on said brackets supporting the body near the bottom in spaced relation to said brackets, dowels on said brackets extending into said body adjacent the top there-

of, an annular support for a cup disposed in concentrically inwardly spaced relation to the top portion of said body, a domed apertured cover, external trunnions on said cover adjacent its open bottom extending in journalled relation through said body adjacent its open top at diametrically opposite sides thereof, means, including the bracket dowels at one side of the axis of said trunnion mounting, for rigidly supporting the ring and affording unobstructed space on the opposite side of the axis of said trunnion mounting between the outside of the ring and the inside of the body for permitting movement of the cover on its mounting into the interior of the body below the ring, and means for releasably latching the cover against movement through said unobstructed space.

4. A single chain suspended censer comprising a group of radially spaced brackets, means connecting said brackets together at the tops, a chain receiving member connected to said means, an ornamental hollow censer body disposed between said brackets, bosses on the brackets for supporting said body in spaced relation to said brackets at the bottom of said body, dowels extending from the brackets into said body adjacent the top, a domed ventilated cover having trunnions adjacent its open bottom journalled at diametrically opposite sides of the open top of the body and selectively movable on its trunnions into the interior of the body, for accessibly exposing the open top thereof, and out of said body for substantially closing the body, an incense cup, an annular support for removably supporting said cup, means disposed on one side of the axis of rotation of said trunnions for rigidly supporting said annular support in spaced concentric relation with the rim of the cover and the top rim of the body and providing on the relatively opposite side of said axis an unobstructed space for movement of the cover between the annular support and the body, and a latch member mounted for rotation with and reciprocation on one of the trunnions for moving the cover and for releasably latching said cover in closing relation to the body.

5. In a censer the combination of three generally C-shaped brackets having horizontal lugs at top and bottom ends thereof, the tops end lugs and the bottom end lugs being respectively stacked and vertically drilled, a securing means for connecting the bottom end lugs together, a foot member connected by said means to the bottoms of the brackets, a hemiglobular, hollow body having an open top and an opening in the bottom, said body supported on and housed between said brackets, a hollow domed hemiglobular ventilated cover of lesser diameter than said body, means pivotally mounting the cover at diametrically opposite sides at the top of said body, an annular support, an incense cup removably supported in said annular support, means disposed at one side of the axis of the pivotal mounting of said cover mounting means for rigidly retaining the annular support in inwardly spaced concentric relation to the top of the body, means to releasably latch the cover in upright relation over said annular support and substantially closing the top of said body and means at the top ends of the brackets for receiving a suspension chain member for the censer.

6. In a censer the combination of a hollow open topped hemiglobular body having an opening in the bottom and an annular series of spaced slots in the top edge thereof, a hollow hemiglobular ventilated cover member of smaller diam-

eter than said body and having external trunnions at diametrically opposite sides, one of which trunnions is journalled in one of said slots in said body, means on said body retaining said last mentioned trunnion in said slot, the cover having slots in the edge thereof matching the remaining slots in the body, a latch rotatable with and reciprocable on the said last mentioned trunnion for permitting alternate manual rotary movement of the cover wholly into and substantially out of the body and for releasably engaging on the body for retaining the cover in the latter position, a group of radially spaced brackets surrounding said body and cover and rigidly supporting the body at its top and bottom, a foot member, a single securing means connecting the foot member and the bottoms of said brackets together, means to secure the brackets together at the tops and a suspension chain receiving member connected to the last 20 mentioned means.

7. A single chain suspension censer comprising radially arranged brackets connected together at the tops thereof, a chain receiving member attached thereto at the connection of the tops of the brackets, a ventilated open topped body supported at its top and bottom on the several brackets, a ventilated cover for said body, trunnions on said cover journalled in the wall of said body and permitting rocking movement of the cover to an inverted position wholly within and in spaced concentric relation with said body, an annular support disposed in inwardly spaced concentric relation to said body and accessibly exposed when said cover is inverted, an incense cup removably supported in said annular sup-

port, and means to releasably latch the cover in a position above the annular support.

8. In a device of the class described the combination of three generally C-shaped brackets each having parallel aligned lugs at the top and bottom respectively, the lugs on successive brackets being in superposed alignment at the top and bottom respectively, a chain receiving member on top of the uppermost lug, means for securing the superposed top bracket lugs and said member together, a chain attached to said member, an open topped and bottom apertured hollow body surrounded by said brackets and secured against movement relative thereto, an annular support for an incense cup disposed in spaced concentric relation within the top interior portion of the body, a ventilated domed cover including a pair of trunnions whereby the cover is journalled in the body and permitting the cover to enter wholly into said body below said annular support, means to latch the cover on the body in an upright position above said annular support, a foot member disposed on the bottom of the lowermost bottom bracket lug and means securing said foot member and the superposed bottom bracket lugs together.
